UNITED STATES PATENT OFFICE

HOWARD I. BECKER, OF SCHENECTADY, NEW YORK, ASSIGNOR TO GENERAL ELECTRIC COMPANY, A CORPORATION OF NEW YORK

ELECTRICAL SYSTEM

Application filed January 3, 1927. Serial No. 158,441.

My invention relates to electrical systems comprising a space discharge device wherein the current transmitted between a cathode and an anode is controlled by means of a grid or control electrode, and has for its principal object the provision of an improved arrangement for controlling the interaction between the grid and anode circuits of such devices.

Various regenerative systems have been provided in the past wherein the grid and anode circuits of a space discharge device are coupled together through a tickler or feed-back coil. The satisfactory operation of such systems has heretofore involved the difficulty that the feed-back coil must be adjusted for each change in the frequency of the potential applied to the grid circuit of the space discharge device. In accordance with my invention, this difficulty is avoided by the provision of means whereby the proportion of the anode current transmitted through the feed-back is varied inversely as the frequency of the grid potential.

My invention will be better understood from the following description when considered in connection with the accompanying drawings and its scope will be pointed out in the appended claims.

Referring to the drawings, Figs. 1 and 2 illustrate regenerative receiving systems wherein my invention has been embodied.

Fig. 1 illustrates a system wherein an antenna 1 and a telephone 2 are interconnected through means comprising a transformer 3, a space discharge device 4, and a source of current shown as a battery 5. The space discharge device 4 is provided with a cathode 6 and a grid 7 which are interconnected through a tuned circuit comprising an adjustable condenser 8 and a winding 9 of the transformer 3 and with an anode 10 which is connected to the cathode 6 through the source 5, the telephone 2 and a feed-back coil 10^a whereby the circuits of the grid 7 and the anode 10 are coupled together. A condenser 11 is provided for shunting the high frequency current past the telephone 2 and source 5, and an impedance device, shown as a resistor 12, is provided for rendering the coupling between the grid circuit and the

coil 10^a substantially independent of the frequency of the voltage applied to the grid.

As indicated in the drawing, both elements of the feed back coupling means, namely, the coupling coil and the impedance device, are fixed or not manually variable in impedance or resistance value, and the coil is in a fixed coupling relation to the circuit to which it supplies feed back energy.

It will be apparent that the system will respond to voltage of a frequency dependent on the adjustment of the condenser 8. Thus assuming the adjustment of this condenser to be so varied that potential of an increasing frequency is applied to the grid 7, the part of the anode current which is transmitted through the feed-back coil 10^a will decrease and the part of the current which is transmitted through the resistor will increase.

Likewise, when the frequency of the grid potential is decreased, the current through the coil 10^a tends to increase and that through the resistor 12 tends to decrease. This variation in the division of the current between the feed-back coil and the impedance device is dependent upon the relation between the impedance of the coil and the impedance value of the device connected in shunt therewith and is of great advantage for the reason

that the feed-back energy, which otherwise tends to increase with frequency and cause the generation of oscillations at high frequency, is maintained substantially constant. In order that the feed-back coupling be unaffected by temperature changes produced by variation in the magnitude of the current transmitted through the resistor 12, it is desirable that this resistor be made of a material having a temperature coefficient of resistance which is substantially zero.

Fig. 2 shows a system which is identical with that of Fig. 1 except that a condenser 13 has been shown as connected in series with the resistor 12. This type of shunt connection has the advantage that its combined impedance is readily made of such a value as to keep the current of the coil 10^a independent of the grid potential frequency. This current should of course be just large enough to maintain the tuned circuit of the

grid in such a state that it is just ready to break into oscillation but is not caused to oscillate by the feed-back current.

In both embodiments of the invention the resistor 12 is the controlling element of the impedance device, its action in the embodiment shown in Fig. 2 being limited by the introduction of the series condenser, the combined impedance of the condenser and resistor then effecting the control of the regeneration. In either embodiment the impedance device is of fixed value.

The embodiments of the invention illustrated and described herein have been selected for the purpose of clearly setting forth the principles involved. It will be apparent, however, that the invention is susceptible of being modified to meet the different conditions encountered in its use and I therefore aim to cover by the appended claims all modifications within the true spirit and scope of my invention.

What I claim as new and desire to secure by Letters Patent of the United States is:

1. The combination of a space discharge device provided with grid and anode circuits, means providing a fixed feed back coupling between said grid and anode circuits, and fixed means connected in shunt to said feed back coupling means of such impedance value with respect to that of said coupling means that the coupling between the grid and anode circuits is rendered substantially independent of the operating frequency of the grid circuit.

2. The combination of a space discharge device provided with grid and anode circuits, a fixed feed back coil providing a coupling between said circuits, and a fixed resistor connected in shunt to said feed back coil, the impedance of said resistor and of said coil being so related that the coupling between the grid and anode circuits is substantially independent of the operating frequency of the grid circuit.

3. The combination of a space discharge device provided with grid and anode circuits, a feed-back coil connected between said circuits, and means comprising a resistor and a condenser connected in series with one another and in shunt to said coil, said shunt connection being so proportioned as to render the amount of energy fed back substantially independent of the frequency.

4. The combination of a space discharge device having an anode circuit and a grid circuit which is tunable over a range of frequencies, a feed back coil in the anode circuit which is coupled to the grid circuit by a fixed coupling, and a fixed impedance device connected in shunt to said feed back coil, the impedance of said last named device and of said coil being so related that the coupling between the grid and anode circuits

is substantially independent of the operating frequency of the grid circuit.

5. The combination of a space discharge device having an anode circuit and a grid circuit which is tunable over a range of frequencies, a feed back coil in the anode circuit which is coupled to the grid circuit by a fixed coupling, and a fixed impedance device connected in shunt to said feed back coil, said device including a fixed resistor and having an impedance value so related to the impedance of said feed back coil that the proportion of the anode current which flows through the feed back coil varies inversely with the frequency of the potential applied to the grid circuit and thereby maintains the energy feed back substantially constant and independent of the frequency supplied to the grid circuit.

In witness whereof, I have hereunto set my hand this 31st day of December, 1926.

HOWARD I BECKER.
